US00D927578S

(12) **United States Design Patent** (10) **Patent No.:** **US D927,578 S**
(45) **Date of Patent:** **** Aug. 10, 2021**

(54) **AXLE ASSEMBLY**

(71) Applicant: **AxleTech International IP Holdings, LLC**, Troy, MI (US)

(72) Inventors: **Christopher G. Baillie**, Lake Orion, MI (US); **Vikram Chopra**, Troy, MI (US); **Shaun Mepham**, Clarkston, MI (US); **Siva Sriniwas Rajeev Mupparti**, Madison Heights, MI (US); **Dan Mircea Stefan**, Windsor (CA); **David John Swica**, White Lake, MI (US)

(73) Assignee: **ALLISON TRANSMISSION, INC.**, Indianapolis, IN (US)

(**) Term: **15 Years**

(21) Appl. No.: **29/664,778**

(22) Filed: **Sep. 27, 2018**

(51) LOC (13) Cl. **15-99**

(52) U.S. Cl.

USPC **D15/149**; D15/5

(57) **CLAIM**

The ornamental design for an axle assembly, as shown and described.

DESCRIPTION

FIG. 1 is a left side, front perspective view of an axle assembly;

FIG. 2 is a left side, rear perspective view of the axle assembly of FIG. 1;

FIG. 3 is a right side, rear perspective view of the axle assembly of FIG. 1;

FIG. 4 is a right side, front perspective view of the axle assembly of FIG. 1;

FIG. 5 is a top plan view of the axle assembly of FIG. 1; FIG. 6 is a bottom plan view of the axle assembly of FIG. 1;

FIG. 7 is a rear side elevational view of the axle assembly of FIG. 1;

FIG. 8 is a front side elevational view of the axle assembly of FIG. 1;

FIG. 9 is a left side elevational view of the axle assembly of FIG. 1; and,

FIG. 10 is a right side elevational view of the axle assembly of FIG. 1.

The features shown in broken lines depict portions of the axle assembly that form no part of the claimed design.

1 Claim, 10 Drawing Sheets

US D927,578 S
